TIRE

John F. Duderstadt, Cuyahoga Falls, and James W. Stiffler, Tallmadge, Ohio, and Harold D. Fetty, Birmingham, Mich., assignors to The Goodyear Tire & Rubber Company, Akron, Ohio

Filed Mar. 7, 1974, Ser. No. 448,849

Term of patent 14 years

Int. Cl. D12—15

U.S. Cl. D12—147

The figure is a perspective view of a tire showing our new design, it being understood that the design is repeated throughout the circumference of the tire as shown schematically by solid line, the opposite side being substantially the same as that shown.

We claim:

The ornamental design for a tire, substantially as shown and described.
